UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CAR-SEAT.

No. 879,730.

Specification of Letters Patent.

Patented Feb. 13, 1908.

Application filed August 9, 1906. Serial No. 328,802.

To all whom it may concern:

Be it known that I, EDWARD G. BUDD, a citizen of the United States, residing at Philadelphia, in the county of Philadelphia and State of Pennsylvania, have invented 5 certain new and useful Improvements in Car-Seats, of which the following is a specification.

This invention concerns car-seats and has 10 reference, more particularly, to the mechanism for supporting the seat-back at the proper angle of inclination permitting reversal thereof from one edge of the seat-cushion to the other and for simultaneously 15 shifting the seat-cushion to raise its forward edge above its rearward edge.

The object of the invention is to so improve 20 the mechanism for supporting the parts and reversing the facing direction of car-seats of the "walkover" type as to provide a compact mechanism which possesses maximum strength, which is so constructed 25 that comparatively small force is required to reverse the seat, and by which the back is held positively against an improper movement throughout the reversal thereof and in the desired relation in its final positions.

My improvements are of particular utility 30 in fireproof seats in which all the parts are made of metal except for the coverings of the cushions.

I have illustrated the preferred embodiment 35 of my invention in the accompanying drawings, in which

Figure 1 is an elevation of the aisle-end of the seat, Fig. 2 is an enlarged transverse section of a portion of the end of the seat as shown in Fig. 1, Fig. 3 is an elevation of the operating mechanism at the aisle-end of the 40 seat as seen from the inner side, and Fig. 4 is a top view of one of the rockers for the seat-cushion.

The drawings illustrate only the mechanism 45 for the aisle-end of the seat but that at the wall-end may be substantially the same as that shown, though preferably, it is supported on the wall of the car instead of the floor.

Referring to the drawings, the aisle-end of 50 the seat is supported on a metallic cricket consisting of two substantially similar parts, each having a body 1 and a leg 2, the adjacent edges of the former being secured together and the ends of the latter being secured 55 to the car floor. At its upper end, this

cricket is provided with integral flanges on which are secured the ends of two connecting rails 3. To the ends of these rails are bolted end connectors or sockets 4 to which is secured a frame-plate 5. This plate is formed 60 to provide a cam surface of peculiar conformation for supporting and guiding a back-supporting arm as hereinafter described; this is preferably done by cutting a slot in the plate the major portion, 6, of which is formed 65 on an arc of large radius and at the ends of the portion 6 are downwardly-extending end portions 7 and 8. At the lower edge of the portion 6 of the slot and at equal distances from the ends 7 and 8 are two rounded cut-away portions 9 and 10. Pivotedly mounted 70 upon the inner side of plate 5 are one or more rollers whose upper surfaces are substantially flush with the lower edge of the slot in the plate; in the drawings, I have shown two 75 such rollers 11 mounted between and close to the offsets 9 and 10 of the slot.

The slot in plate 5 is adapted to receive and guide two rollers 12 and 13 pivotally mounted on the lower end of a back-supporting arm 80 14 which moves back and forth adjacent to the plate 5. This arm extends upward and is secured at its upper end to the back-cushion 27 of the seat, a socket-plate 15 being secured over the upper end of arm 14. 85 The lower end of arm 14 is of considerable width and the rollers 12 and 13 thereon are at a distance apart equal to the distance between either end of the slot in plate 5 and the offset 9 or 10 adjacent thereto.

In the plate 5 is a central opening forming 90 a bearing for the end of a rod 16 and secured on this rod is a lever 17. The end of this lever extends up adjacent to arm 14 and is provided with a pin 18 which extends 95 through an elongated slot in arm 14. This pin has an enlarged head to prevent the pin from slipping through the slot, this head being flattened on opposite sides to permit of readily assembling and disassembling the 100 parts. Below the rod 16, lever 17 is bent inwardly of the seat and its lower end is provided with a segmental gear 19. This gear meshes with a rack 20 on the rocker 21 for the seat-cushion 22. Rocker 21 is mounted 105 to slide back and forth in rocker-runs formed in the sockets or end connectors 4 and on its lower edge has cam surfaces 23 which serve to alter the angular relation of the rocker as it moves in the rocker-runs. On its upper 110

edge, the rocker has dowel-pins 24 adapted to enter holes in the under side of the seat-cushion frame to support the cushion and move it as the rockers are moved.

5 In Fig. 4, a top view of the rocker 21 is shown, from which it will be seen that the teeth of the rack 20 are separately formed and project from the side of the rocker so that dust cannot settle in and partially fill the 10 spaces between them and prevent smooth working of the parts.

A cover-plate 25 of metal is secured in any suitable manner on the outer side of plate 5 over the slot therein and serves to hold the 15 parts of the plate against relative movement under the strains to which they are subjected. A seat-end 26 is secured to plate 5 to conceal the operating mechanism and extends upward above the plane of the seat-cushion, its upper edge supporting an arm-rest. This seat-end is preferably formed of sheet-metal and is of attractive design.

The operation of the seat as thus constructed will now be described.

25 In the position of the parts shown in Figs. 1 and 3, the back 27 is supported by the rollers 12 and 13 on the back-supporting arm 14 bearing on the cam surface formed by the lower edge of the slot in plate 5, the 30 roller 12 lying at the bottom of the downwardly-turned end portion 8 and the roller 13 lying in the cutaway portion 10. The back is held at the proper inclination with relation to the vertical as the roller 13 is 35 above the roller 12. In reversing the facing direction of the seat, force is applied to the back in the horizontal direction. At the beginning of the movement of the back, the rollers 12 and 13 ride up on the lower inclined edges of the end 8 and the offset 10, respectively, of the slot in plate 5, these edges being arranged to diverge somewhat in the upward direction, and the back is raised slightly and turned angularly to approach the vertical more closely. When 40 rollers 12 and 13 are in the substantially flat portion 6 of the slot, the movement of the back is practically a horizontal one so that very little force is required to move it, this 45 being further decreased by the anti-friction roller or rollers 11 which are engaged by the lower edge of arm 14 and, to a large extent, take the weight of the back off rollers 12 and 13. As the back moves along, the coaction 50 of pin 18 with the slot in arm 14 turns lever 17 and the rod 16 to which it is secured, the pin 18 moving to the upper end of the slot and back again to the lower end during the reversal of the back. When roller 12 is 55 directly over the offset 10 in the slot in plate 5, there is no downward movement of the back such as would carry the roller into the offset since the roller 11 adjacent to the offset is in engagement with the bottom of arm 14 and supports the latter. Similarly the

roller 13 is prevented from moving into offset 9 by the roller 11 adjacent to that offset. While the rollers are moving across the portion 6 of the slot, which is curved on an arc of large radius, the angular relation of the back with reference to the vertical is changed slightly and when roller 13 reaches the end of the portion 6 it moves down to the end of the downwardly-turned portion 7; at the same time, roller 12 moves down to the end of the offset 9 and the back is in its final position.

It will be seen that the sides of the offsets 9 and 10 adjacent to the ends of plate 5 are curved over to form projections indicated at 28, Fig. 3, under which the roller on arm 14 80 will lie when it is at the bottom of the offset and the back is in its final position. The coaction of pin 18 with the slot in arm 14 precludes such movement of the back as will cause roller 12 to lodge on top of the projection 28; as above stated, pin 18 moves to the top and then down again to the bottom of the slot during the reversal of the back and it reaches the lower end as the roller 12 approaches a position over projection 28, thus 85 precluding further movement in this direction. The roller is free, however, to move down into offset 9, and while doing this, pin 18 moves away from the bottom of the slot in arm 14 a very slight distance. But when 90 roller 12 is in its final position at the bottom of slot 9, the projection 28 extends so far around the roller as to preclude any movement thereof under the weight of the occupant of the seat against the back. The 95 other roller 13 rests in the bottom of the end portion 7 and therefore the back is firmly held in its operative position. The coaction of gear 19 and rack 20 causes movement of 100 rockers 21 and the seat-cushion carried 105 thereby as the back is moved, in a direction opposite to the direction of movement of the back and the cam surfaces 23 on the rockers operate to raise the forward edge of the seat above its rearward edge. Rod 16 to which 110 the levers 17 at both ends of the seat are secured serves to synchronize the movements at both ends of the seat.

It will be seen that the mechanism of the seat as thus constructed is very compactly arranged and that on account of the shape of the slot in plate 5 with the major portion thereof curved on an arc of long radius, the plate can be of comparatively small width. This shaping of the slot gives the further advantage that the back is raised vertically only a small extent in reversing, and therefore a small amount of force is required to reverse the seat.

Having now described my invention, what 125 I claim as new therein and desire to secure by Letters Patent is as follows:—

1. In a reversible car-seat, the combination of a frame, a movable back, a back-supporting arm, a cam surface on said frame 130

having a large central substantially horizontal portion, downwardly-turned portions at the ends of said central portion and offsets equidistant from said ends, and parts 5 on said arm coacting with said cam surface to guide the back in reversing and with said ends and offsets to support the back, substantially as set forth.

2. In a reversible car-seat, the combination of a frame, a movable seat, a movable back, a back-supporting arm, a cam surface on said frame having a large central portion, downwardly-turned portions at the ends thereof and offsets in said central portion 10 equidistant from said ends, parts on said arm coacting with said cam surface to guide the back in reversing and with said ends and offsets to support the back, a pivotally-mounted lever connected to said arm by a pin-and-slot connection, and means actuated by said lever for moving said seat, substantially as set forth.

3. In a reversible car-seat, the combination of a frame, a movable back, a back-supporting arm, a metallic plate secured to said frame having a slot therein, said slot having a central, substantially horizontal portion, downwardly turned end portions and offsets intermediate the ends of the slot, a metallic 25 plate secured to said first-named plate over said slot to conceal the slot and strengthen the plate, and parts on said arm entering said slot and coacting with the walls thereof to guide the back in reversing and with said 30 offsets and the ends of the slot to support the back, substantially as set forth.

4. In a reversible car-seat, the combination of a frame, a movable back, a back-supporting arm, a plate secured to said frame 40 and having a slot therein, said slot having a large central portion, downwardly-turned portions at the ends thereof and offsets equidistant from the ends of the slot, and parts on said arm entering said slot and coacting 45 with the walls thereof to guide the back in reversing and with said ends and offsets to support the back, substantially as set forth.

5. In a reversible car-seat, the combination of a frame, a movable back, a back-supporting arm, a cam surface with which said arm coacts to guide the back in reversing, said surface having an offset and a roller mounted adjacent to said cam surface and coacting with said arm to support the same 55 in moving over said offset, substantially as set forth.

6. In a reversible car-seat, the combination of a frame, a movable back, a back-supporting arm, a cam surface on said frame 60 having a large central portion, downwardly-turned portions at the ends thereof and offsets equidistant from the ends of the cam surface, parts on said arm coacting with said

cam surface to guide the back in reversing and with said ends and offsets to support the back, and a roller mounted adjacent to said cam surface and coacting with said arm, substantially as set forth. 65

7. In a reversible car-seat, the combination of a frame, a movable back, a back-supporting arm, a cam surface on said frame having offsets therein, and parts on said arm coacting with said cam surface to support the back, one of said parts being adapted to move over and the other into one of said offsets in moving the back to an operative position and said offsets being formed to coat with the part therein to hold the latter against movement due to pressure upon the operative surface of the back, substantially as set forth. 70 75 80

8. In a reversible car-seat, the combination of a frame, a movable back, a back-supporting arm, a cam surface on said frame having a large, central, substantially horizontal portion, downwardly turned portions at the ends of said central portion and offsets equidistant from said ends, and parts on said arm coacting with said cam surface to guide the back in reversing and with said ends and 90 offsets to support the back, said offsets being formed to hold said back against movement due to pressure on the operative surface of the back, substantially as set forth. 85 90

9. In a reversible car-seat, the combination of a frame, a movable back and a back-supporting arm, a cam surface on said frame having a large central, substantially horizontal portion, downwardly turned end portions and offsets intermediate the ends, parts on 100 said arm coacting with said cam surface to guide the back in reversing and with said ends and offsets to support the back, and a pivotally mounted lever connected to the back by a pin-and-slot connection, said lever 105 guiding the back in its movement of reversal but being out of supporting relation to the back when the latter is in operative position, substantially as set forth. 95

10. In a reversible car-seat, the combination of a frame, a movable back, a back-supporting arm, a cam surface on said frame having a large central, substantially horizontal portion, downwardly turned end portions and offsets intermediate the ends of the cam 115 surface, and parts on said arm coacting with said cam surface to guide the back in reversing and with said offsets and the ends of the cam surface to support the back, substantially as set forth. 110 120
